(57) **CLAIM**

The ornamental design for a palm wrench, as shown and described.

DESCRIPTION

FIG. 1 is a top side perspective view of a palm wrench illustrating my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a bottom side perspective view thereof.

The broken line showing of the core is for the purpose of illustrating portions of the palm wrench and forms no part of the claimed design.
